UNITED STATES PATENT OFFICE.

JOSEPH BARKHEIMER, OF DES MOINES, IOWA.

ELECTRIC BURGLAR-ALARM.

SPECIFICATION forming part of Letters Patent No. 319,053, dated June 2, 1885.

Application filed April 25, 1884. (No model.)

To all whom it may concern:

Be it known that I, JOSEPH BARKHEIMER, of Des Moines, in the county of Polk and State of Iowa, have invented an Improved Electric 5 Burglar-Alarm, of which the following is a specification.

My invention consists in the construction and combination of circuit-closing devices with swinging doors and conducting-wires and to an electric bell, as hereinafter fully set forth, in such a manner that the opening of the door will close a circuit and ring the bell, and also in such a manner that when a person removes a panel from a solid door or the woven-wire 15 covering from a screen-door and attempts to pass through, the circuit will be closed and the bell rung to sound an alarm.

Figure 1 of the accompanying drawings is a perspective view of a section of a doorway 20 and a section of a screen-door to which my devices are applied. Fig. 2 is a plan view of the arrangement of the parts fixed to the top of the doorway. Fig. 3 is a view of a transverse section of a doorway and transverse 25 vertical sections of doors hinged to the doorway.

Jointly considered, these figures clearly illustrate the construction, application, and operation of my complete invention.

30 A represents the top facing in a doorway or frame.

Nos. 1 and 2 are conducting-wires fixed in parallel position and near the edges of the facing A by means of staples, or in any suitable way. They extend through one of the 35 sides of the frame and doorway and terminate in hooks or eyes that adapt them to be detachably connected with conducting-wires Nos. 3 and 4, that extend to the opposite poles 40 of a battery, and electric bell located in the hall or other suitable position inside of a dwelling or other building.

B is a spring-wire fixed to the wire No. 1 and bent into such a form that it will extend 45 across the wire No. 2 and project past the shoulder and door-stop C. A knob may be formed on its free end to prevent it from penetrating or marking the door with which it comes in contact. In its normal condition 50 this spring-wire and circuit-closer will press against the wire No. 2, as required, to con-

nect the two wires Nos. 1 and 2, for the purpose of ringing the bell; but when the door D is closed it will engage the free end of the wire B and push it away from the wire 55 No. 2, and the two wires Nos. 1 and 2 will be thus disconnected and the circuit opened as required to maintain the battery inoperative and the bell silent. It is therefore obvious that the door cannot be opened without closing the circuit and ringing the bell unless the wires 1 and 3 or 2 and 4 are disconnected.

F F are spring-wires fixed to the wire No. 2 in such a manner that they will, in their normal condition, press upon the wire No. 2 60 and close the circuit.

G is a duplex spring pivoted against the top and inside of the frame of a screen-door, H, in such a manner that the free ends of the spring G will, when the door is closed, engage 70 the free ends of spring circuit-closing wires F and press them away from the wire No. 1 and open the circuit, as required, to make the battery and bell inoperative. Opening the screen-door H allows the springs F to resume their 75 normal positions, as required to close the circuit and ring the bell.

J J represent cords or wires fastened to the lower end and inside of the door and to the free ends of the duplex spring G at the top of 80 the door in such a manner that they will retain the spring in a horizontal position, as required to operate the circuit-closers F, and also as required to close the circuit and ring the bell when an entrance is effected through 85 the closed screen-door H. In warm seasons the inner solid doors, D, are frequently left open and the screen-doors closed for excluding persons and to admit fresh air, and burglars seek entrance by cutting away the wire 90 screen from the door-frame and passing through the closed frame. Pressure against either one of the cords or wires J will be transmitted to the spring G and withdraw one of its ends from one of the circuit-closers F and 95 allow it to resume its normal position, close the circuit, and ring the bell.

Breaking or cutting either one of the wires J will allow the duplex spring to turn sufficiently on its pivot to produce the same result, so that pressing or severing either one of the wires J when the screen-door is closed 100

will cause an alarm to frighten the depredator and to notify the inmates of an attempted burglary.

I claim as my invention—

5 The combination of conductors Nos. 1 and 2, fixed in a door-frame, the conducting-wires Nos. 3 and 4, connected with an electric bell, the spring-wires and circuit-closers B and F,

the duplex spring G, and cords or wires J, and two doors, substantially as shown and described, to operate in the manner set forth, for the purposes specified.

JOSEPH BARKHEIMER.
